MACHINE FOR REMOVING BARK FROM LOGS.

No. 878,848.

Specification of Letters Patent.

Patented Feb. 11, 1908.

Application filed July 27, 1907. Serial No. 385,856.

To all whom it may concern:

Be it known that I, GEORGE S. WITHAM, Jr., a citizen of the United States of America, residing in Sandy Hill, in the county of Washington and State of New York, have invented certain new and useful Improvements in Machines for Removing Bark from Logs, of which the following is a specification.

My invention relates to that class of rossing machines in which the log is held in the path of a vertically arranged rotary disk armed with knives which remove the bark from the log, and in which the log is turned or rotated to present its entire bark covered surface to the action of the knives.

The object of my invention is to improve the construction of such machines, increase their output, render them, as far as possible, automatic, relieve the attendant of most of the labor heretofore necessary in the operation of the mechanism, and to prevent waste by an improper adjustment of the knives or a careless manipulation of the logs.

In carrying out my invention, I provide an endless carrier on which the logs are placed by an attendant and which conveys the logs to a position to be acted on by the knives and then transfer them to a conveyer which carries them away from the machine to any desired point. When the log reaches the proper position to be cut, the carrier is automatically stopped and the log is automatically removed from the carrier by a vertically movable table which holds the log during the cutting operation, and which, when the bark is removed, lowers and transfers the log to the carrier which is automatically started and which transfers it to the conveyer that carries the log away from the machine. The table is provided with an automatic stop which automatically rises when the table commences to move upward and prevents the log from moving endwise to too great an extent when it is first delivered to the table. This stop is automatically withdrawn when the table lowers whereby the log may be moved from the table by the endless carrier. I also provide an adjustable stop which prevents the log from moving endwise while the bark is being cut therefrom.

The log is turned while being cut by means of spur-wheels mounted in a swinging frame which is normally held elevated, but which is automatically lowered to cause the spur-wheels to engage the log when the log is ele-

vated by the table and removed from the endless carrier. Means is provided whereby the position and movement of the spur-wheel may be controlled at will by the attendant and other means is provided whereby the attendant may, at will, control the up and down movement of the table. I have also provided means whereby the rotation of the spur-wheels may be controlled to accommodate irregularities in the form of the log. The table is provided with means for rotating the log which are positively driven and co-operate with the spur-wheels above the log.

Ordinarily in setting the knives the services of two attendants are required, one on the front side of the disk to observe the amount of protrusion of the knife edge, while the other behind the disk effects the adjustment. I have provided gages or stops which are so arranged as to be out of the path of the log during the rotation of the disk, but which automatically gage the amount of protrusion of the knives so that by merely adjusting the knives on their seats they may be set to protrude to the proper extent and without measurement.

In this class of machines it is sometimes desirable to have the disk revolve in one direction and sometimes in the other direction. I have so formed the casing or housing of the disk as to provide discharge openings on opposite sides and I have provided the disks with two seats for each knife inclined in opposite directions so that the knives may be set properly on the disk for rotation in either direction. I have also provided means whereby the disk may be locked while the knife is being set and also means whereby the disk may be suspended in its frame when the bearings of the disk shaft are being changed.

Other features of my invention will be hereinafter explained.

In the accompanying drawings—Figure 1 shows a front elevation of a rossing machine embodying my improvements. Fig. 2 is a detail view of the log carrier and one of its supporting wheels. Fig. 3 shows an end elevation of the machine with some parts in section. Fig. 4 is a detail view in perspective of part of the mechanism above the log for rotating it. Fig. 5 is a perspective view on an enlarged scale showing particularly the log elevating table and certain parts associated therewith. Fig. 6 is a detail view in section and on an enlarged scale showing

the construction of the seats for the knives and the gages or stops for limiting the protrusion of the knives. Fig. 7 is a detail view in perspective of one of the stops. Fig. 8 is a sectional diagrammatic view illustrating particularly the relation between the log, its table and the upper rotating means for the log. In Fig. 8 the table is shown in its lowermost position. Fig. 9 is a view similar to Fig. 8 with the table elevated and the upper log rotating means lowered into engagement with the log. Fig. 10 is a perspective view of one of the teeth or spurs employed in the spur-wheels of the upper log rotating means. Fig. 11 is a detail view of one of the spur-wheels, and Fig. 12 shows a further detail thereof. Fig. 13 is a diagrammatic view mainly in front elevation but partly in section of the entire machine showing how the logs are carried from a pond past the rossing machine and delivered to a conveyer which carries them away from the machine. Fig. 14 shows a vertical transverse section through the machine with certain parts in elevation, and illustrates particularly how the rotary disk is supported and how it may be hung from its casing when the bearings of its shaft are being changed. Fig. 15 is a detail view of the devices for locking the disk when the knives are being changed.

In Fig. 13 I have shown logs, X, in a pond, A, from which they are taken by an endless carrier, B, and delivered to the machine for the removal of their bark. After the bark is removed the logs are transferred by the chain to a conveyer, C, of suitable construction and delivered at any desired point.

The casing or housing, D, for the rotary disk, E, is in most respects similar to that heretofore employed. It has an opening at D' to permit the logs to come in contact with the knives and it is provided with two discharge openings, D², for the exit of bark, chips, dirt, &c. Only one of these openings is used at a time. When the other is not in use it may be closed by a plug or stopper, D³, but by thus constructing the casing it may be used "right or left", that is, the knife carrying disk may be revolved in either direction. The casing is preferably made in sections hinged at d and locked by bolts at d'. By removing the bolts, d', the upper section may be thrown back and the disk removed or the parts within the casing exposed for repairs.

The disk, E, is attached to a shaft, F, which extends through openings in the front and rear walls of the casing. The front bearing, F', for the shaft is supported on a bracket, F², carrying wedges, F³, which may be adjusted by screws, F⁴, to raise and lower the bearing to any desired extent to properly center the disk either originally or after the 65 bearings have become worn. The rear bearing,

ing, F⁵, of the shaft, F, is supported on a bracket, F⁶. A pulley, H, fast on the rear end of the shaft, F, may be belted to a line shaft, or any other suitable source of power. An idle pulley, H', fast on a shaft, h, is arranged close to the pulley, H, and the shaft, h, is mounted to rotate in double bearings, h'. The driving belt may be shifted from one pulley to the other to start or stop the rotation of the disk by a belt shifter, H², operated by a handle, H³.

Should it be desired to change the bearings after they are worn, the disk and its shaft may be supported by means of a screw, I, extending through a threaded socket in the top part of the casing and adapted to engage a threaded socket, i, in the disk. Without this device, when the bearings are being changed the machine would have to be dismantled and the shaft would have to be jacked up outside the casing which is less convenient.

The cutting blades or knives, J, are of usual construction and they extend through openings, j, in the disk. The disk is provided with seats, E', for the knives and it will be observed by reference to Fig. 6 that duplicate seats are made for each knife and that they are inclined oppositely so that the knives may be set to operate properly when the disk is revolved in either direction.

It is important that the knives should protrude from the front side of the disk to such an extent as to remove all the bark without removing any or much of the log. 100 Much difficulty has heretofore been encountered from an improper adjustment of the knives. Sometimes they have been made to protrude to too small an extent so that the bark is not completely removed, or a 105 much longer time than necessary is taken to operate upon the log, and sometimes the workmen, in order to increase the output of the machine within a given time, have made the knives protrude to too great an extent 110 and thus the log is cut into injuriously so as to remove not only the bark but also the good wood which should be saved. By my improvements an improper adjustment of the knives is impossible. I arrange at each 115 end of the slotted opening, j, in the disk a stop or gage, K. These stops are so arranged that they will not come in contact with the log or any part of the machine as the disk rotates, but will nevertheless present the full length of the knife or a sufficient length thereof to operate upon the log properly.

These stops are preferably of the form shown in Fig. 7, each one being merely a strap having wings, k, receiving screws, k', that attach it to the disk and a central portion, k², recessed at k³, to receive the knife. In setting a knife on its seat the attendant may operate through an opening or man-hole, K², (Fig. 13). He merely has to loosen 120

the screw, K³, and shove the knife forward until its forward movement is arrested by the stop, K, and he can then tighten the screw, K³, to hold the knife in its adjusted 5 position.

In order to hold the disk steady while the adjustment of the knives is being effected, I provide a locking device, L, shown most clearly in Fig. 14. It will be observed that 10 the disk, E, is provided with a series of radial openings, i. These are all threaded to accommodate the screw, I, heretofore referred to, but they are adapted to also receive the end, l, of a locking bolt, L', which is arranged 15 to move radially through the casing, D. This bolt extends through a frame, L², attached to the casing and carries on its outer end a hand wheel L³. It also carries arms, L⁴, which are adapted to ride on a cam surface, L⁵, of the frame, L². This cam surface is formed on a cross-piece, L⁶, on the outer 20 end of the frame, and between this cross-piece and a collar, L⁷, on the bolt, L', is arranged a spiral spring, L⁸, which normally 25 tends to move the bolt radially inwards.

In Fig. 15 the bolt is shown as being withdrawn from the disk and it is held in this withdrawn position by means of the arms, L⁴, being supported on the raised portions of 30 the cam surface, L⁵, but when the hand wheel is turned to allow the arms to enter the depressed surfaces of the cam, L⁵, the spring, L⁸, will operate to move the bolt, L', radially inwards and the bolt may be made 35 to engage with a socket, i, and lock the disk so that it cannot move while the knives are being adjusted. A corresponding socket, i, is provided for each of the knives.

The carrier is preferably composed of two 40 parallel endless chains provided with teeth or spurs, b, adapted to bite into the log and insure its being elevated and carried forward. The carrier passes over duplicate sprocket wheels, B', mounted in the pond, A, and its 45 upper side passes over sprocket wheels, B², at the top of the pond, thence over wheels B⁴, on the opposite side of the machine, thence back to idle wheels, B⁵, carried by a bracket, B⁶, and thence over sprocket wheels, 50 B⁷, and then to the wheels, B', before mentioned. The wheels, B⁴, are carried by a shaft, B⁸, mounted in suitable bearings and carrying a wheel, B⁹, which is adapted to be 55 engaged by a paper covered friction wheel B¹⁰, mounted on the power shaft, B¹¹, which carries the driving pulley, B¹². This shaft is mounted in bearings in a sliding block, B¹³, the arrangement being such that the wheel, B¹⁰, may be moved into and out of engagement with the wheel, B⁹, so that the chain 60 may be made to move or to stop in the manner hereinafter described.

The carrier, B, as before stated, delivers the logs, after the bark is removed, to a conveyor, C, which may be of any desired con-

struction. That shown is well known and need not be further described.

I have provided means whereby when the log reaches a proper position relatively to the cutter disk, it may be removed from the 70 carrier and held while being barked. If the log were allowed to remain on the chains while being barked, the chains would not properly hold it owing to the flexible nature of the chains. For the purpose of thus lifting the log from the carrier, I have provided what I call a table, M, which is arranged to move up and down to a limited extent to lift the log from the carrier and then to replace it thereon. This table comprises a 75 front portion, m, a bottom portion, m', and upwardly projecting side pieces, m², on each side at the sides of which are openings, m⁴, to accommodate the carrier chains. To the bottom of the table is attached a yoke-shaped frame, M⁵, which is connected with a bar or piston, M⁶, passing through a guide frame, M⁷, on the top of an engine cylinder, M⁸.

The piston rod is provided with a piston 80 within the cylinder, M⁸, and it is adapted to be reciprocated by the engine in such manner as to raise and lower the table. The details of the engine need not, of course, be specifically shown or described. It may be 85

of any suitable construction. The valve chamber, M⁹, of the engine is connected with a supply pipe, M¹⁰, for the entrance of steam, air or other suitable motive fluid, and the valve rod, M¹¹, for controlling the admission and exhaust is connected with a lever, M¹², jointed to the piston rod, M¹⁰, which operates in a cylinder, M¹³, provided with suitable valve mechanism at M¹⁴, controlling the admission of air, steam or other suitable fluid 90 through the supply pipe, M¹⁵. The valve mechanism is operated by a rod, M¹⁶. The arrangement is such that by operating the rod, M¹⁶, the lever, M¹², may be operated to control the admission and exhaust for the cylinder, M¹³, and thus raise and lower the table. This control may be effected by 95 means of a lever, M¹⁷, jointed to the rod, M¹⁶, at m⁵, and pivoted to the casing, D, at m⁶.

I have provided means, however, by which the table may be raised automatically as soon as a log reaches its proper position thereon. As shown in Fig. 5, spur-wheels, O, are attached to a shaft, o, having its bearings in brackets, O², attached to the front of the casing, D. The outer end of this shaft at o', is unsupported and the shaft carries a cog-wheel, O³, gearing with an intermediate wheel, O⁴, meshing with a larger cog-wheel, O⁵, carrying a stud or pin o², adapted to engage a lever, O⁶, pivoted to the main frame at O⁶, and connected with the rod, M¹⁶. When the table is in its lowermost position, as shown in Fig. 5, the spur-wheels, O, project above its top and are adapted to engage 100

105 110 115 120 125 130 135

the underside of the log while the latter is on the carrier, B. As the carrier moves the log across the table the spur-wheels are rotated and by properly gearing these spur-wheels with the wheel, O⁴, the pin, o², may be made to trip the lever, O⁵, at the proper time to actuate the mechanism to raise the table. Ordinarily logs presented to the machine are 24 inches long, occasionally they are 18 10 inches in length and sometimes 30 inches long. Preferably the arrangement is such that when 18 inches of log has moved across the spur-wheels, the lever, O⁵, is tripped and the table is caused to rise so that the table- 15 raising mechanism will be operated whether the log be 18, 24 or 30 inches in length.

The table is provided with supporting rollers, P, and also with a fluted feed-roller, P', which is geared at P², with a vertical 20 shaft, P³, which is adapted to move vertically as the table moves up and down in the manner hereinafter described.

It will be understood that one attendant may place the logs on the carrier, that the 25 logs are moved automatically by the carrier to the table when the table is in its lower-most position, that when the log has reached the desired position on the table, the latter is automatically raised and means is provided, as will next be described, whereby the 30 movement of the carrier is arrested so that the next log will not be fed to the table or towards the table until the table is again lowered and is ready to receive another log. 35 For the purpose of thus arresting the movement of the log carrier the table is pivotally connected at q with a bell-crank lever, Q, pivoted at q', to a standard, Q², and connected at q³, with the sliding block, B¹³, before 40 referred to. When the table is in its lower-most position the friction wheel, B¹⁰, engages the wheel, B⁹, and the log-carrier is moved, but when the table rises the friction wheel, B¹⁰, is withdrawn from the wheel, B⁹, 45 and the movement of the carrier chain is arrested. It will thus be seen that the table is made to rise automatically at the proper time and the movement of the log carrier is at the same time automatically stopped, 50 and it will also be seen that when the table is lowered the movement of the log carrier is automatically resumed. The table is not arranged to lower automatically after the log is barked. The lowering of the table is 55 effected by the attendant who operates the lever, M¹⁵.

The momentum given to the logs by the carrier chains tends sometimes to carry them too far across the table. In order to 60 prevent this, I provide an automatic stop which is shown as consisting of an arm, R, projecting upwardly from a lever, R', arranged horizontally below the table having one end pivoted to the frame; D, at R², and 65 having a pin and slot connection, R³, with

an arm, R⁴, projecting downwardly from the table. The arm, R, has a pin and slot connection, R⁵, with one side of the table and the leverage is so calculated that when the table is in its lower position the stop, R, is withdrawn or lowered, but when the table commences to rise the stop is quickly moved up above the plane of the top of the table into the path of the log. The leverage is also such that as soon as the table commences to descend the stop is quickly withdrawn so that by the time the top of the table reaches the plane of the carrier chains, the stop is out of the way and the log can be removed from the table by the carrier. This automatic 75 disappearing stop is of great advantage in the operation of the machine.

In order to move the logs from the front portion of the table onto the roller P' to press them against the cutter disk and to rotate 80 them while being cut, I provide spur-wheels, S, carried by a swinging frame, S', and rotated by a driving chain, S², connected with a shaft, S³. The frame, S', comprises arms, s, hung loosely from the shaft, S³, and carrying at their outer lower ends an axle, S⁴, to which the wheels, S, are secured. The axle, S⁴, also carries a sprocket wheel, S⁶, (Fig. 1) 85 over which the chain, S², extends and this chain extends over a sprocket wheel, S⁶, secured to the shaft, S³. Each of the arms, s, 90 is pivotally connected with a link, S⁷, the outer end of which is slotted and bifurcated and receives an arm, t, of a bifurcated lever, T. Each arm, t, carries a bolt, t', which extends through the slot of the link, S⁷. A spring, t², is interposed between each arm, t, and each arm, s, rings or washers, t³, being arranged at the ends of the springs. Normally the lever, T, is held in a position to 95 raise the frame, S', to the position shown by dotted lines in Fig. 3 with the spur-wheels, S, away from the log. At this time the bolts, t', will be at the upper ends of the slots in the outer ends of the links, S⁷, but when the front end of the lever, T, is depressed, the frame, S', carrying the spur-wheels, S, will be lowered to the position shown by full lines in Fig. 3. In thus lowering, the wheels first 100 engage the log when the table is elevated to the position shown in Fig. 9, and when the log is at the front of the table. Then as the frame S' swings downward and inward and the wheels rotate the log is moved over against the cutting disk and onto the roller 105 P', as shown in Fig. 9. The springs, t², are put under compression so as to hold the frame down with a yielding pressure whereby it may accommodate itself to irregularities in the shape of the log. If the spur-wheels were held rigidly in their lowermost 110 position, the rotary movement of the log would sometimes be stopped when a knot or other irregularity presented itself, but by providing the yielding devices described the 115 120 125 130

rotary movement may continue uniformly without interruption. Furthermore the arrangement is such that the wheels S engage the log gradually or with a yielding pressure and thus they are prevented from cutting too deeply at any time. If the springs t^2 were omitted the spur-wheels S would strike the logs so forcibly when the frame S' is lowered that much of the good wood would be taken off below the bark before the rotation of the log would commence.

The spur-wheels, S, are raised and lowered and caused to rotate automatically in the manner next to be described. The shaft, S³, is mounted in suitable bearings at the top of the casing, D, and is capable of sliding longitudinally in its bearings to a limited extent. At one end the shaft, S³, carries a beveled wheel, T', machined smoothed which engages a beveled pinion, T², made of paper or covered with paper, on a shaft, T³, carrying a pulley, T⁴, which is belted to a pulley, T⁵, on the shaft, F, of the knife carrying disk. The shaft, S³, carries a collar, T⁶, between which and a loose collar, T⁷, on the shaft is interposed a spiral spring, T⁸. The collar, T⁷, bears against one of the bearings, T⁹, of the shaft and the spring tends to hold the wheel, T', and pinion, T², in engagement with each other, and when thus engaged the shaft, S³, is made to rotate and in turn rotates the spur-wheels, S. By reason of the frictional gearing between, T', and T², should any great obstruction be presented to the rotation of the wheels, S, the gearing will slip. The gearing may be separated so as to arrest the rotation of the wheels, S, by means of a bell-crank lever, T¹⁰, pivoted at t¹⁰, to the casing, D, and connected by a rod, T¹¹, with a pedal or foot lever, T¹². By means of this pedal the rotation of the feed wheels, S, may be arrested to permit a knot or seam to be removed from the log without elevating the frame, S'.

On one end the shaft, S³, carries a beveled pinion s¹⁰, engaging a beveled pinion, s¹¹, on the shaft, P³. When the shaft, S³, rotates, movement is imparted not only to the spur-wheels, S, but also to the fluted feed roller, P'. The shaft, P³, has a slot and pin connection at p³, with the frame and with the pinion, s¹¹, so that this shaft may rise and fall with the table without separating the gears, s¹⁰, s¹¹, or the gearing at P². The teeth of the pinions, s¹⁰, s¹¹, are made long or deep so that the longitudinal adjustment of the shaft, S³, does not throw them out of gear, it being understood that a very slight movement of the shaft is sufficient to separate the friction gearing at T', T². It will be understood that the shaft, S³, rotates continuously or as long as the gears, T', T², engage each other, but the spur-wheels, S, are at times held up away from the log or the horizontal plane of the log. In order to raise and lower the spur-

wheels, S, automatically, I provide the mechanism next to be described.

The rear end of the lever, T, is jointed to a vertical connecting rod, U, connected with a piston, U', operating in a cylinder, U², to which steam, air or other suitable fluid is admitted through a valve chest, U³. The valve is connected by a rod, U⁴, with a lever, U⁵, to the front end of which is connected a rod, U⁶, extending up through lugs, U⁷, projecting laterally from one side of the table, M. On the upper end of the rod, U⁶, is a collar, u, between which and another collar, u', resting on the top lug, U⁷, is a spring, U⁸. Another spring, U⁹, is arranged between a collar, u², fast on the rod, U⁶, and another collar, u³, resting against the under side of lower lug, U⁷. A hand lever, U¹⁰, is pivoted to the table at u¹⁰, and it is jointed to the rod, U⁶, between the lugs, U⁷. When the table is in its lowermost position the rear end of the lever, T, is lowered and the feed wheels, S, are in their elevated position, but when the table rises the rod, U⁶, causes the rod, U⁴, to be drawn downward and the valve mechanism causes the rod, U, to rise and the frame, S', carrying the spur-wheels, S, to be lowered. It will thus be seen that the upward movement of the table automatically moves the spur-wheels, S, against the log and that the downward movement of the table withdraws the spur-wheels from the log. By means of the hand lever, U¹⁰, the attendant may move the spur-wheels to or from the log when the table is in either position, thus putting the mechanism under perfect control without in any way interfering with the operation of the automatic mechanism. The springs, U⁸, U⁹, might be dispensed with, but they serve to afford a yielding connection to reduce strain on the mechanism.

The spur-wheels, S, may be of any suitable construction, preferably they are formed in the manner indicated in Figs. 10, 11, and 12, each wheel consisting of a disk, W, having a channelled periphery, w, in which the teeth, w', are held, preferably by set screws, w². The inner ends or shanks of the teeth are preferably made to match as indicated in Fig. 11. Each tooth is separately secured by a set screw and any of the teeth may be removed and sharpened or replaced by a new one when necessary.

In machines of this class some of the bark, chips and dust is thrown across the front side of the machine instead of being drawn into the casing and discharged through the port D². In order to collect such bark, dust and chips, and prevent its being scattered on the outside of the machine, I provide a hood, Y, arranged at one side of the table and connected by a pipe or conduit, Y', with the casing, D, at its middle portion as shown in Fig. 14. The cutter disk is provided with

fan wings, E², as usual, which tend to draw chips, dirt, etc., in through the opening, D', and in my machine it also draws the chips, dirt, etc., in through the hood, Y, and conduit, Y', to the interior of the machine and delivers them through the discharge opening, D².

The rotary cutter disk when operating on a log tends to move it in the direction in which the disk is rotating. In most machines of this class a stop or buffer is provided to prevent this endwise movement of the log while being turned and barked. In my machine I employ a stop, Z, consisting of a head, z, on an arm, z', connected with a horizontally arranged rack, z², adapted to slide in guides, z³, and engaged by a pinion, z⁴, rigidly connected with a lever, z⁵, having a handle, z⁶. By means of these devices the stop, Z, may be adjusted longitudinally with reference to the table so as to hold the log, whatever be its length, in proper relation to the cutters and the feed mechanism for rotating the log. The lever, z⁶, may be provided with suitable detent mechanism, as shown, for holding the stop rigidly when once set.

In my machine most of the operations are automatic while still being under perfect control. One attendant is required to place the logs on the log carrier while one other attendant can control the rossing operation without expending any energy in either lifting the logs, holding them against the cutters, or turning them. When a log arrives at the table, the latter is automatically raised and operates mechanism which throws the log against the cutters and holds it there while the bark is being removed and the attendant has merely to wait until the log is barked. By then merely turning a lever the log with the bark removed may be lowered onto a carrier which conveys it away and brings forward another log which is automatically raised from the carrier and barked, and so on.

45 I claim as my invention:—

1. A machine for removing bark from logs comprising a cutter, a carrier for conveying the bark covered logs toward the cutter, a table for automatically removing a log from the carrier and for supporting it while being cut, and means for automatically bringing into operation mechanism for pressing the log against the cutter and for turning it while being so supported and pressed.

55 2. A machine for removing bark from logs, comprising a cutter, a carrier for conveying bark covered logs toward the cutter, a table for removing a log from the carrier, power operated mechanism for raising and lowering the table, power operated mechanism which yieldingly presses the log against the cutter while being cut and which turns it during the cutting operation, and means for bringing into operation said log pressing and

turning means after the log has been removed from the carrier.

3. A machine for removing bark from logs, comprising a cutter, a carrier for conveying bark covered logs toward the cutter, a table for removing a log from the carrier, means for moving the log into engagement with the cutter, for pressing it against the cutter and for turning it while being cut, power driven means for bringing into operation said log moving pressing and turning means, means for causing the barked log to be delivered to the carrier and for causing the latter to resume its movement and carry the barked log away, and means under the control of the attendant for regulating the pressure of the log turning means on the log during the progress of the cutting operation.

4. A machine for removing bark from logs comprising a vertically arranged rotary disk armed with radial knives, a carrier for moving logs toward the cutter, a table for lifting a log from the carrier, means for pressing the log against the cutter during the cutting operation and for turning it while being cut, a stop for preventing endwise movement of the log during the cutting operation, power driven mechanism for elevating and lowering the table, power driven mechanism for elevating and lowering the log-pressing and turning means and devices under the control of the attendant for regulating the action of the power driven mechanisms.

5. A machine for removing bark from logs comprising a cutter, a carrier for conveying logs toward the cutter, a table which supports a log while being cut, power operated mechanism for lifting the table to elevate the log above the carrier, means for throwing such mechanism into and out of operation, means for holding the log on the table for pressing it against the cutter and for turning it while being cut, power operated mechanism for moving such holding, pressing and turning means into and out of engagement with the log and devices for throwing such last-mentioned operating mechanism into and out of operation.

6. In a machine for removing bark from logs, the combination of a rotary cutter, a carrier for conveying bark covered logs toward the cutter, a vertically movable table for lifting a log from the carrier, fluid pressure mechanism for raising the table, devices operated by the log while on the carrier for causing such fluid pressure mechanism to raise the table, means for pressing the log against the cutter during the cutting operation and for turning it while being cut, fluid pressure mechanism for bringing said log pressing and turning means into engagement with the log and devices operated by the table for causing said fluid pressure means to operate.

7. In a machine for removing bark from logs, the combination of a rotary cutter, a carrier for conveying bark covered logs toward the cutter, a vertically movable table for lifting a log from the carrier, fluid pressure mechanism for raising the table, devices operated by the log while on the carrier for causing such fluid pressure mechanism to raise the table, means for pressing the log against the cutter and for turning it while on the table and during the cutting operation, fluid pressure mechanism for bringing said log-pressing and turning means into engagement with the log, devices operated by the table for causing said fluid pressure mechanism to operate and other devices under the control of the attendant for regulating the action of said last-mentioned fluid pressure mechanism.

20 8. A machine for removing bark from logs comprising a cutter, a carrier for conveying bark covered logs toward the cutter, means for automatically removing a log from the carrier, means for automatically arresting the movement of the carrier as a log passes to the table, means for automatically bringing into operation mechanism for pressing the log while on the table against the cutter and for turning it during the cutting operation and devices for delivering the barked log to the carrier and for causing the latter to resume its movement and carry the barked log away.

9. In a rossing machine the combination with a cutter, of a horizontally movable log-carrier, a vertically movable table for removing a log from the carrier and for holding it while being cut, means set into operation by the log while on the carrier for causing the table to rise and lift the log from the carrier and means for turning the log while on the table during the cutting operation.

10. In a rossing machine the combination with a rotary cutter, of a horizontally movable log-carrier, a vertically movable table across which the carrier passes, means set into operation by a log while on the carrier for causing the table to rise and lift the log from the carrier and means for then bringing into operation mechanism for pressing the log against the cutter and for turning it while still supported by the table during the cutting operation.

11. In a rossing machine the combination with a cutter, of a log-carrier, a table for removing a log from the carrier and for holding it while being cut, means operated by the log as it approaches the cutter for automatically effecting the movement of the table to withdraw the log from the carrier, and means for pressing the log while on the table against the cutter and for turning it during the cutting operation.

12. In a rossing machine the combination

with a cutter of a log-carrier, a table for removing a log from the carrier, means set into operation by the movement of the table for arresting the movement of the carrier and means for turning the log while on the table during the cutting operation.

13. In a rossing machine the combination with a cutter of a log-carrier, a table for removing a log from the carrier, a stop carried by the table for limiting the movement of the log as it passes on to the table, means operated by the log as it passes on to the table for automatically effecting the movement of the table to withdraw the log from the carrier, means operated by the upward movement of the table for withdrawing the stop carried thereby, a stop against which the end of the log abuts during the cutting operation, means for pressing the log against the cutter and for turning it during the cutting operation and means under the control of the attendant for lowering the table to deliver the barked log.

14. In a rossing machine the combination with a cutter of a horizontally movable log-carrier, a vertically movable table for removing a log from the carrier, means for pressing the log against the cutter and for turning it while being cut and means operated by the movement of the table for arresting the movement of the carrier.

15. In a rossing machine the combination with a cutter of a log-carrier, a table to which the carrier delivers a log, means operated by the log while on the carrier for automatically operating the table to remove the log therefrom, means for at that time automatically arresting the movement of the carrier, and means for pressing the log against the cutter and for turning it during the cutting operation.

16. In a rossing machine the combination with a cutter of a horizontally movable endless carrier, a vertically movable table for removing a log from the carrier and holding it while being cut, means for turning the log while on the table during the cutting operation and mechanism for starting and stopping the carrier and for raising and lowering the table.

17. In a rossing machine, the combination with a cutter, of a horizontally movable carrier, a vertically movable table for removing a log from the carrier, means operated by the log while on the carrier for causing the table to remove the log from the carrier, means for yieldingly pressing the log against the cutter during the cutting operation and for turning it while being cut, and mechanism set into operation after the table has removed the log from the carrier for bringing into operation said log pressing and turning means.

18. In a rossing machine, the combination with a cutter, of a horizontally movable car-

rier, a vertically movable table for removing a log from the carrier and holding it while being cut, mechanism operated by the log while on the carrier for causing the table to 5 remove the log from the carrier, means operated by the movement of the table for arresting the movement of the carrier, means for yieldingly pressing the log against the 10 cutter during the cutting operation and turning it while being cut, and mechanism set into operation after the log has been raised by the table for operating said log pressing and turning means.

19. In a rossing machine, the combination 15 with a cutter of a horizontally movable carrier, a vertically movable table for removing a log from the carrier and holding it while being cut, mechanism for raising and lowering the table, wheels engaged by the log while on 20 the carrier and connections between these wheels and the raising and lowering mechanism whereby the rotation of the wheels causes the table to be raised.

20. The combination of a cutter, a log-carrier, a table which receives logs from the carrier, means operated by a log while on the carrier for automatically raising the table, devices under the control of the attendant for actuating said operating mechanism whereby 25 the table may be raised and lowered at will, and means also under the control of the attendant for pressing the log against the cutter while on the table and for turning it during the cutting operation.

35 21. In a rossing machine the combination with a rotary cutter of a log-carrier, means for removing a log from the carrier, means for automatically stopping the movement of the carrier as soon as the log is removed 40 therefrom, and means automatically set into operation when the log is removed from the carrier to press the log while on the table against the cutter and to turn the log during the cutting operation.

45 22. In a rossing machine the combination with a rotary cutter of a horizontally movable log-carrier, means for removing a log from the carrier, means for stopping the movement of the carrier as soon as the log is removed therefrom, and means automatically set into operation when the log is removed from the carrier but while on the table to press the log against the cutter and to turn it during the cutting operation.

55 23. In a rossing machine the combination of a rotary cutter, a table for supporting a log while being cut, means for raising and lowering the table, means for turning the log while on the table during the cutting operation, connections between the log-turning means and the table for causing said turning means to rise and fall as the table moves vertically, and means for controlling the up and

down movement of the log-turning means independently of the movement of the table. 65

24. In a rossing machine the combination of a rotary cutter, means for holding a log while being cut, mechanism located above the log for turning it while the cutting operation is in progress, power driven mechanism for actuating said log-turning mechanism and for raising and lowering it which mechanism contains slip or friction gearing whereby the log-turning mechanism is thrown into and out of operation when an obstruction 70 is encountered, and a spring interposed in the lifting and lowering mechanism for causing the turning mechanism to exert a yielding pressure on the log.

25. In a rossing machine the combination 80 of a rotary cutter, means for holding a log while being cut, mechanism for turning the log while undergoing the cutting operation, a frame in which said turning mechanism is carried, power driven mechanism for raising 85 and lowering said frame, and for operating the turning devices and which contain slip or friction gearing and a spring interposed in the lifting and lowering mechanism for causing the turning devices to exert a yielding 90 pressure on the log.

26. In a rossing machine, the combination 95 of a rotary cutter, means for supporting a log while being cut, a spur wheel for turning the log, a swinging frame in which said spur wheel is mounted, a lever for raising and lowering the frame, power operated mechanism for operating the lever to raise and lower the frame, a link extending upwardly from the swinging frame, a sliding connection between the link and the lever, a spring interposed between the lever and the frame, power driven mechanism for rotating the spur wheel and devices under the control of the attendant for regulating the power 105 driven means to raise and lower the wheel.

27. In a rossing machine the combination 110 of a rotary cutter, a log-carrier, a table across which the carrier extends and which receives a log from the carrier, a stop carried by the table for preventing the log being moved to too great an extent across the table, means operated by the table for withdrawing the stop as the table rises and for bringing it into operative position when the table descends, 115 and another fixed stop against which the log abuts during the cutting operation.

28. In a rossing machine the combination 120 of a cutter, a log-carrier, a vertically movable table which receives logs from the carrier, a lever having a fixed pivot, and provided with an arm projecting above the top of the table, and a pivotal sliding connection between the lever and the table whereby the arm of the lever is lowered and raised as the table rises 125 and falls.

29. In arossing machine the combination of a rotary cutter, a table for holding a log while being cut, a roller carried by the table, log-turning means above the table, means for raising and lowering said log-turning means, means for raising and lowering the table and connections between said roller on the table and the log-turning means whereby

the former is operated while the table is free to raise and lower.

In testimony whereof, I have hereunto subscribed my name

GEORGE S. WITHAM, JR.
